UNITED STATES PATENT OFFICE.

ADDIE W. COOKE, OF MEMPHIS, TENNESSEE.

WINDOW GUARD.

Application filed July 22, 1926. Serial No. 124,271.

My present invention relates generally to window guards and more particularly to an inner window guard to prevent ready entry through an open window by unwarranted persons, my primary object being the provision of a guard more especially intended for sleeping rooms, which will permit of effective ventilation and at the same time secure the desired end in so far as safety is concerned.

A further object of my invention is the provision of a window guard of sectional construction, which may be folded in disuse, and which in its folded position will present a neat, compact appearance at one side of the window frame.

In the accompanying drawing which illustrates my invention and forms a part of this specification:—

Figure 1 is a perspective view showing the practical application of my invention, the window guard being in its extended operative position.

Figure 2 is a vertical section taken therethrough substantially on line 2—2 of Fig. 1.

Figure 3 is a horizontal section through the device in its folded position, and;

Figure 4 is a detail horizontal section through one of the hinge connections illustrating the use of spring means to assist in the folding of the sections after use.

Referring now to these figures and particularly to Fig. 1, I have shown a window guard generally indicated at 10, extending laterally across the lower portion of a window opening and attached at one side as by means of a vertical series of screws or like fastening members 11, in a rigid manner to one side 12 of the window casing inwardly beyond the lower sash 13, which in the use of my improved guard, will be in its upper position.

My improved guard includes a series of sections hingedly connected along their adjacent lengthwise or vertical edges, as at 14, so that the sections can be extended across the window casing or opening, as in Fig. 1, or folded one upon the other at one side of the window opening, as illustrated in Fig. 3, the section 15 at the free end of the guard being solid or imperforate throughout while the remaining sections 16 have a series of perforations or openings 17 which provide for ventilation of the room wherein the guard is employed.

The section 15 is also provided with a hasp

member 18 hinged to its free edge at a point substantially below the upper edge of the guard and adapted for extension over a staple 19 anchored in any suitable manner adjacent to the other side 20 of the window frame so as to provide for the use of a lock 21, by means of which the guard as a whole may be securely fastened in its effective position across the window opening.

When the guard is folded as in Fig. 3, so that its several sections flatwise engage one another against the side 12 of the window frame to which the guard is screwed or otherwise attached, the hasp 18 may be employed over a staple 22 either as a simple hook or so that a lock 23 may be used to prevent unwarranted tampering with the guard, the solid or imperforate section 15 of the guard acting in this position as a protecting cover for the series of perforate sections.

I may also employ a construction as shown in Fig. 4, wherein springs 24 are employed in connection with the hinge joints between the several sections of the guard to flex the latter and assist in the ready folding of the sections upon one another to the inactive position of Fig. 3, and where such a construction is employed I may utilize a swinging clasp 25 to engage the opposite side of the folded sections with respect to the hasp 18. This clasp 25 will be loosely connected at one end to the outer edge of the side 12 of the window frame, so that when the guard is extended in the operative position as shown in Fig. 1, the clasp 25 may be dropped to vertical position to prevent interference with curtains, shades and the like, used in connection with the window.

My improved guard may thus be mounted ready for instant use at any time without presenting an unsightly appearance adjacent to the window, while it is in its folded position, and will insure safety and at the same time permit of ample ventilation.

I claim:—

1. A window guard adapted to be secured at one end to one inner side of a window casing and consisting of a series of sections hingedly connected to one another to fold and unfold laterally across the window opening of the frame, and means carried in connection with the section at the free end of the guard adapted to similarly provide for its secure fastening in both its folded and unfolded positions.

2. A window guard adapted to be secured at one end to the one side of the window casting, and including a series of foldable sections arranged to fold and unfold across the 5 window opening of said frame, the said guard having a solid imperforate section at its free end and having its remaining sections perforate whereby to provide for venti-

lation when in its effective position, the imperforate section forming a cover for the 10 remaining perforate sections when the guard is folded at one side of the window frame, and means to secure the guard in both its effective and folded positions.

Mrs. ADDIE W. COOKE.
